UNITED STATES PATENT OFFICE.

FREDERICK W. KOHLMYER, OF CLEVELAND, OHIO.

GUARD FOR POLISHING OR GRINDING WHEELS.

1,027,548.

Specification of Letters Patent.

Patented May 28, 1912.

Application filed January 18, 1912. Serial No. 671,854.

To all whom it may concern:

Be it known that I, FREDERICK W. KOHLMYER, citizen of the United States, residing at Cleveland, in the county of Cuyahoga and State of Ohio, have invented certain new and useful Improvements in Guards for Polishing or Grinding Wheels, of which the following is a specification.

This invention relates to hoods for polishing or grinding wheels, and has for its object to provide an improved hood which can be moved out of position when desired.

A further novel feature is a grating in the hood to catch small articles that may drop while being polished.

The invention is illustrated in the accompanying drawings in which—

Figure 1 is a side elevation of the device. Fig. 2 is a section, on the line 2—2 of Fig. 1. Fig. 3 is a side elevation opposite to Fig. 1. Fig. 4 is a front view of the hood detached from the suction pipe.

Referring specifically to the drawings 6 indicates the hood or guard properly shaped 25 to partially cover or inclose the buffing, grinding or polishing wheel 7, which turns on its shaft 10. The hood has a notch 12 for the shaft to fit in. At the bottom the hood is flanged as indicated at 13 to slide in a 30 channeled flange or guide 14 at the mouth of the suction pipe 9, through which the dust and dirt are exhausted. The guides 14 are open at the rear end, so that the hood can be slid in or out to remove and replace same

when necessary, or it can be adjusted back 35 and forth according to the desired exposure of the wheel 7, to accommodate large or small work, such adjustment being indicated in dotted lines in Fig. 3. A latch 8 engaging over the front edge of the tube 9, serves 40 to hold the hood in its usual position.

The mouth of the tube 9 is provided with a small wire grating 11 which rests thereon and which serves to catch small articles which may be dropped into the hood or beside the wheel while being polished. This 45 grating is held in position by the hood which fits around the same.

What I claim is:

1. In a guard for a polishing wheel or the like, the combination with a suction pipe having opposite guides at the mouth thereof, of a hood provided with flanges at opposite sides slidable in said guides, whereby the hood may be removed, and a latch carried by the hood and engageable with the pipe, to hold the hood in position thereon.

2. The combination of a suction pipe, a hood thereon, and a grating resting on the mouth of the suction pipe, the hood fitting 60 around the edge of the grating, to hold the same in position.

In testimony whereof, I do affix my signature in presence of two witnesses.

FREDERICK W. KOHLMYER.

Witnesses:

JOHN A. BOMMHARDT,
STEDMAN J. ROCKWELL.
